TRIMMING MECHANISM FOR SEWING MACHINES

Harry E. Smallbone, New York, N. Y., assignor to Willcox & Gibbs Sewing Machine Company, New York, N. Y., a corporation of New York

Application June 9, 1932. Serial No. 616,330

6 Claims. (Cl. 112—125)

This invention relates to trimming mechanism for sewing machines and especially to such mechanism designed for use in conjunction with a binder in the well-known lock-stitch machine of the Willcox & Gibbs Sewing Machine Company to constitute a lock-stitch trimming and binding machine.

The principal object is to provide a trimming mechanism of efficient, simple and relatively inexpensive construction, whereof the reciprocating bar carrying the movable trimmer blade may be readily locked to its driving connections to be actuated thereby, or detached from said driving connections and locked to a fixed part of the machine to thereby locate the movable trimmer blade and its associated parts in an out-of-the-way position when trimming of the work is not desired.

This and other objects and advantages which will be apparent from the following detailed description, are realized by the embodiment of the invention illustrated in the accompanying drawings wherein—

Fig. 1 is a front elevation of the left-hand end of the machine showing the needle part way up and the trimmer latch engaged with driving connections which actuate the movable trimmer bar and its blade;

Fig. 2 is a similar view, but with the trimmer bar and its blade locked in an elevated out-of-the-way position by engagement of the latch with a fixed part or keeper on the machine frame;

Fig. 3 is an end elevation from the left of Fig. 1;

Fig. 4 is a view in elevation on line 4—4 of Fig. 1;

Fig. 5 is a transverse section on line 5—5 of Fig. 1;

Figs. 6 and 7 are perspective views of the trimmer bar sleeve and the latch respectively; and

Fig. 8 is a perspective view showing the latch engaged with its fixed part or keeper on the machine frame.

Referring to the drawings, 20 is the machine base having supporting legs such as 21 (Fig. 3). 22 is the needle-hole plate having therethrough needle-hole 23 (shown in dotted lines in Fig. 3) as well as slots 24 through which rows of teeth 25 of the four-motion feed dog 26 operate in the usual way to engage and feed the work. An opening through the top plate of the machine base 20, such as usually provided to afford access to the mechanism beneath, is closed by the usual slide plate 26 (Figs. 1 and 3). 27 is an upstanding

edge guide secured to or formed integrally with a plate 28. Screws 29 passing through a slot in plate 28 adjustably secure said guide 27 in the desired position to guide to the trimmer blades the fabric edge which is to be trimmed before a binding is applied and secured thereto by the stitch-forming mechanism.

35 is an opening through the base plate 20 at the right of the forward end of needle plate 22, as shown in section in Fig. 2. 37 is the lower and stationary trimmer blade adjustable in a groove 36 (Fig. 3) in the face of an upright plate 38, the latter being rigidly supported from the base plate 20 in a manner which it is unnecessary to here describe. A piece of thin sheet metal, 70 bent to form a rear wall 39 and a side wall 40, is secured to the under side of base plate 20 by a bracket member 41 (Fig. 2). Said walls 39 and 40 together with plate 38 constitute a trough-like conduit for receiving trimmings of fabric removed by the trimmer blade.

50 is a part of the outer end of the arm of the sewing machine frame to which the hollow head 51 of the machine is secured by three screws 52, Figs. 1 and 4. 53 is the main driving shaft extending horizontally through arm 50 into head 51 where it carries a trimmer bar driving eccentric 54 (Fig. 4), a needle bar driving crank 55 (Fig. 3) and a block 56, which latter rotates in and projects slightly from an opening 57 in the wall of the machine head 51. A rotary take-up, not shown, is secured to block 56 by a screw 58 and a dowel pin 59.

60 is the needle bar carrying needle 61 at its lower end and driven from the crank pin 62 of crank 55 by pitman 63 which at its upper end pivotally engages said pin and at its lower end is connected by a pivot screw 64 to a vertically movable slide 65 which latter at one end is clamped to the needle bar 60 and at its other end 90 slides on the presser-foot bar next mentioned.

66 is the presser-foot bar carrying presser-foot 67 positioned to overlie the needle-hole plate 22 and particularly the slotted portions thereof through which the rows of teeth of the feed member operate. The usual presser-foot lifting lever 68 is shown in Fig. 3.

More detailed description and illustration of these parts of the mechanism is unnecessary.

A trimmer bar 70, vertically movable in upper bearing 71 and lower bearing 72 on the machine head 51, carries at its lower end a vertically reciprocating trimmer blade 73, adjustably clamped in place by a clamp plate 74 secured by a screw 75, and a trimmings deflector plate 76 secured 110

in place by a screw 77. Scraps of fabric removed from the body fabric by the trimmer blades are deflected by the vertically reciprocating plates 76 into the before-mentioned conduit constituted by 5 the plate 38 and the associated walls 39 and 40 of sheet metal.

80 is a trimmer-bar actuating member in the form of a sleeve embracing and freely slideable upon trimmer bar 70 below its upper bearing 71. 10 The enlarged lower end of sleeve 80 has a projecting guide finger 82 (Figs. 2 and 6), a transverse notch or groove 83 above said finger, and an ear or lug 84 into which is screwed a pivot stud 85 of ball formation. During the running of the 15 machine, sleeve 80 is constantly reciprocated vertically on trimmer bar 70 by a lever 86 (Fig. 4), fulcrumed at one end on the machine frame by a screw stud 87, at its other end embracing the spherical portion of the stud 85, and at its middle 20 embracing the eccentric 54 of the main shaft and being actuated thereby through the intermediary of upper and lower bearing blocks 88, 88, slideable in an opening in the lever closed at its top by a cap plate 89.

25 A fixed latch member in the form of an upright bar 90, secured to the machine head by the screws 91, is curved at its upper end and terminates in a right angle extension 92 which constitutes a keeper adapted to be engaged by a latch 30 next described.

The lower portion of the trimmer bar 70 is of larger diameter than its upper portion, thereby forming a shoulder at 100. A latch support 101 embraces bar 70 immediately above and in contact with said shoulder 100 and is split at 102 (Fig. 5) so that it may be contracted by a screw 103 and thus clamped tightly to the bar. An extension 104 from support 101 engages the aforesaid guiding slot 93 and thus prevents turning 40 of the trimmer bar on its axis during its vertical reciprocation. Another extension 105 from support 101 has a circular extremity with a milled top or gripping surface.

A latch generally in the form of a bell crank 45 lever is best shown in Fig. 7. It comprises an upright arm 106, terminating at its upper end in a bent over extremity 107 adapted to engage either the notch 83 of the sleeve 80, or over the upper edge of extension or keeper 92, and a horizontal arm 108 terminating in a circular part 109 having a milled bottom surface for gripping purposes. At its middle said latch spans the latch support 101 and is pivoted thereto by screw stud 110. A vertical slot 111 in arm 106 is slidably 55 engaged by, and acts as a guideway for, finger 82 of the sleeve 80. A coiled spring 112 is interposed between the circular extremities of the extension 105 and arm 108 of the latch and tends to engage the latter in locking position, either 60 with the notch 83 of the reciprocating trimmer sleeve, or with the stationary keeper 92 fixed to the machine frame.

In the operation of the machine, when it is desired to trim fabric edges, the end 107 of the latch 65 is engaged with notch 83 (as shown in Fig. 1) and so held by spring 112, whereby the reciprocations of sleeve 80 are imparted through said latch to the trimmer bar 70 and its movable trimmer blade 73. On the other hand, when trimming 70 of fabric is not required, the circular ends of fixed extension 105 and arm 108 of the latch lever are gripped between the thumb and finger and forced together against the pressure of spring 112 until the latch is disengaged from notch 83 of the

trimmer sleeve. Then the latch mechanism and along with it the parts at the lower end thereof (including the movable trimmer blade 73) are slid upward until the latch is engaged with its keeper 92 with all of the parts in the position shown in Figs. 2 and 3. In this manner the movable trimmer blade and associated parts may be quickly elevated to and locked in an out-of-the-way position when trimming is not required. The procedure can be quickly reversed when trimming is desired.

What is claimed as new is—

1. Sewing machine trimming mechanism comprising in combination, cooperating fixed and movable trimmer blades; a reciprocatory trimmer-bar carrying said movable blade; an actuating member for said trimmer-bar and slideable thereon; driving means for reciprocating said actuating member; and means carried by said trimmer-bar and movable to either connect or disconnect said bar and actuating member. 90

2. Sewing machine trimming mechanism comprising in combination, cooperating fixed and movable trimmer blades; a reciprocatory trimmer-bar carrying said movable blade; an actuating member for said trimmer-bar and slideable thereon; and means carried by said trimmer-bar and movable for either connecting said bar to or disconnecting it from said actuating member, or for connecting said bar to and disconnecting it from a fixed part of the machine. 100

3. Sewing machine trimming mechanism comprising in combination, cooperating fixed and movable trimmer blades; a reciprocatory trimmer-bar carrying said movable blade; an actuating member for said trimmer-bar and slideable thereon; and a latch carried by said trimmer-bar for either connecting or disconnecting said bar and actuating member. 110

4. Sewing machine trimming mechanism comprising in combination, cooperating fixed and movable trimmer blades; a reciprocatory trimmer-bar carrying said movable blade; an actuating member for said trimmer-bar and slideable thereon; and a latch for either connecting said trimmer bar to said actuating member or connecting it to a fixed part of the machine out of action. 115

5. Sewing machine trimming mechanism comprising in combination, cooperating fixed and movable trimmer blades; a reciprocatory trimmer-bar carrying said movable blade; an actuating member for said trimmer-bar and slideable thereon; driving means for reciprocating said actuating member; and a latch carried by said trimmer-bar and acting either to engage said actuating member to impart movement of the latter to the bar, or to engage a fixed part of the machine and thereby hold the trimmer-bar out of action. 125

6. Sewing machine trimming mechanism comprising in combination, cooperating fixed and movable trimmer blades; a reciprocatory trimmer-bar carrying said movable blade; an actuating sleeve for said bar and slideable thereon; a latch carrier secured to said bar; and a spring actuated latch pivotally mounted on said latch carrier and acting to engage either said actuating sleeve to impart movement therefrom to the trimmer-bar, or to engage a fixed part of the machine and thereby hold the trimmer-bar out of action. 140

HARRY E. SMALLBONE.
